FOREIGN PATENT DOCUMENTS

KR 113992 S * 5/1991

Primary Examiner—Melanie H Tung*Assistant Examiner*—Lavone D Tabor(74) *Attorney, Agent, or Firm*—Fulbright & Jaworski L.L.P.(57) **CLAIM**

The ornamental design for a brush handle, as shown and described.

DESCRIPTION

FIG. 1 is a top front perspective view of my design;

FIG. 2 is a front view of my design;

FIG. 3 is a back view of my design;

FIG. 4 is a right side view of my design;

FIG. 5 is a left side view of my design;

FIG. 6 is a top view of my design; and,

FIG. 7 is a bottom view of my design.

The dashed lines in FIGS. 1–7 are environmental structure forming no part of the claimed design. All other surface(s) or portion(s) of my design not shown in the figures or otherwise described in the specification form no part of the claimed design.
